MATCH HOLDER

Rodney S. Pullen, Akron, Ohio, assignor to
 Pullenlite Company, Philadelphia, Pa., a corporation of Pennsylvania

Application July 13, 1933, Serial No. 680,249

11 Claims. (Cl. 206—31)

My invention relates to match holders, and particularly to holders for packets which contain matches adapted to light upon withdrawal from the packets.

5 A purpose of my invention is to support a match packet of the pull-and-light variety by means extending between the folds of the packet.

A further purpose is to introduce a supporting tongue between the folds of a packet of matches adapted to light on withdrawal, and to extend the tongue transversely of the matches in contact with the fold between the bottom and the side of the match packet, so that pull upon the match sticks for the purpose of withdrawal will 15 not dislodge the packet.

A further purpose is to support a match packet against movement laterally of the matches and in the direction of the stick-ends of the matches by a tongue extending between the folds of the packet, and, desirably also, to support the packet against movement in the direction of the head ends of the matches by a plate engaging the bottom of the packet spaced from the tongue.

25 A further purpose is to hold a plurality of match packets in generally parallel relation by spaced, generally parallel, tongues extending between the folds of the respective packets.

A further purpose is to support a pull-and-light match packet by resilient means, so that, when a match is withdrawn, the packet will be resiliently pulled away from the match while the match is being pulled out of the packet, thus giving a higher resultant striking velocity.

30 A further purpose is to support a packet for matches which ignite upon withdrawal by suction-gripping means, so as to permit attachment to any suitable object, whether horizontal or otherwise, such as a desk top, window, automobile windshield, etc., and ignition of the matches by simply pulling on the ends of the match sticks.

A further purpose is to pivotally connect the base of a match holder with the portion of the device which grips the match packet, so that the ends of the matches may be directed at any one of a plurality of angles with respect to the base.

45 A further purpose is to hold a match packet in a selected one of a plurality of possible angular positions by pressure of a resilient abutment.

50 Further purposes will appear in the specification and in the claims.

I have chosen to illustrate one only of the possible devices in which my invention might be embodied, selecting the form shown primarily from the standpoint of cheapness and satisfac-

tory operation, but also because it illustrates the principles involved without unnecessary complication, and without involving the reader in tedious details.

Figure 1 is a perspective view of my improved match holder containing two packets of pull-and-light matches.

Figure 1a is a fragmentary perspective view corresponding to Figure 1.

Figure 2 is a central longitudinal section of the device of my invention, with two match packets 10 illustrated for placement purposes.

Figure 2a is a fragmentary enlargement of Figure 2, with a typical packet in place.

Figure 3 is a section of Figure 2 upon the line 15 3—3.

Figure 4 corresponds to Figure 2, but shows the match packets in a different angular position with respect to the base.

Figure 5 is a top plan view of the blank from 20 which one part of my holder may be made.

Figure 6 is a section corresponding to part of Figure 2, but showing match packets of the type of my Patent No. 1,694,864, granted December 11, 1928.

In the drawing like numerals refer to like 25 parts.

I intend my improved holder to be used with match packets which ignite the match while it is being withdrawn from the holder. Such match packets are shown in my Patent No. 30 1,694,864, granted December 11, 1928 and No. 1,782,074, granted November 18, 1930, and in my applications, Ser. Nos. 569,631, filed October 19, 1931; 587,563, filed January 19, 1932 and 629,708, filed August 20, 1932. 35

The specific detail of the pull-and-light match packet is not important to my invention, and therefore I have not described the match packets in great detail, merely referring to my earlier developments for general information as to the type of match packet involved. The match packets 40 15 comprise matches 16 arranged in a row and positioned by a wrap 17 which is folded about the matches, and allows the match sticks to extend through openings 18. The interior of the wrap is provided with suitably located match-striking material for igniting the matches when they are withdrawn by a longitudinal pull 45 exerted by the user, who grasps the stick ends 20 of the matches, beyond the top 19 of the packet. On one side of each packet the outer side layer or fold 21 of the wrap is, for at least part of its extent, free from attachment to the adjoining interior portion 22 of the packet. 50

It will be evident that fastening means may extend through the outer side layer or fold 21, or adhesive may be applied to the inner surface of the outer layer or fold 21, provided the attachment or adhesive does not extend over the full length of the packet, or can be easily broken over part of the length of the packet.

At the lower end of the outer side layer or fold 21 of the packet, there is normally a folded corner or edge 23, at which the outer side layer or fold 21 joins the bottom 24 of the packet.

Usually the packets of pull-and-light variety are provided with flap extensions 25, to protect the stick ends 20 of the matches. In the case of insertion of the matches into a holder, it is desired that the stick ends 20 be accessible, and accordingly the flap extensions 25 may desirably be folded down out of the way.

My novel holder comprises generally three parts, the gripping mechanism 26 which engages and holds the match packets, the base 27 which supports the gripping mechanism, and the connection 28 between the gripping mechanism 26 and the base 27.

It will be evident that the gripping mechanism 26 may be used with any type of base or with any type of connection between the base and the gripping mechanism, although the special form of base shown has peculiar advantages.

The primary operating member of the gripping mechanism 26 is a tongue 29, desirably consisting of sheet metal, and preferably considerably wider than it is thick. The tongue 29 is suitably supported at its base 30, but is otherwise free from support both at its top edge 31 and at its lower edge 32, so that it may extend into the match packet between its folds, and preferably between the outer side layer or fold 21 and the interior portion of the packet 22, as shown in Figure 1. The tongue 29, being preferably of considerable width, prevents the match packet from rocking laterally and thus supports the matches against lateral movement. The lower edge 32 of the tongue 29 preferably engages the interior of the fold line 23 between the outer side layer or flap 21 and the bottom 24 of the packet, thus preventing longitudinal movement of the packet toward the stick ends 20 of the matches when a pull is applied to the stick ends to withdraw one or more matches. The spreading action exerted by the tongue 29 also increases the pressure on the match striking surface of the packet, and thus causes more positive match ignition when the matches are withdrawn. Likewise, the tongue 29 provides a firmer background for the match striking surface.

For easy insertion of the match packet into the holder, the forward ends of the tongue 29 are curved at 33.

In the form of my holder illustrated in the drawing, I show two tongues 29 whose bases 30 are supported by an intermediate portion 34 which is bent up from a bottom plate 35 which extends across the bottom of the tongues substantially parallel to the lower edges 32 of the tongues. The tongues 29 are substantially parallel to one another and are separated from the bottom plate 35 by a narrow slit 36 which receives the bottom 24 of the match packet.

The bottom plate 35 prevents movement of the match packet toward the head ends of the matches, since it holds the bottom 24 of the match packet close against the lower edge 32 of the tongue. While it would be possible to obtain much of the advantage of my invention without

the use of the bottom plate 35, I consider it desirable for most uses.

In order to assist in still further gripping of the lower end of the packet, I provide extensions 37, bent up at right angles from the bottom plate 35 and slightly outside the tongues 29. The extensions 37 prevent the possibility of shifting of the fold line at 23 or crumpling of the outer side layer or fold 21 when the matches are withdrawn.

The packet-gripping means could, as I have already noted, be mounted upon a base of any suitable type.

However, I much prefer to use a base having suction-gripping means as shown because such means provides attachment between the match holder and the adjoining structure which prevents bodily movement of the match holder when an effort is made to withdraw a match. Were it not for the suction-gripping means, the match holder would either require physical attachment to adjoining structure, or would have to be rather heavy, as considerable force is exerted when a match is withdrawn. The suction-gripping means also assists in striking a match, as will be later explained, and permits the use of the match holder in places where it could not otherwise be employed, such as attaching to vertical surfaces like windows or automobile windshields, and securing in places where it otherwise would be knocked off, such as desk tops, chair arms, etc.

The base 27 which I show is preferably of soft rubber, and consists of a head 38 and annular resilient suction-gripping flanges 39 cupped to leave a space 40 beneath the flanges when the suction-gripping means is pressed against a flat object. The flat lower surface of the head 38 is coated with gum or other suitable adhesive at 39.

The attachment between the packet-gripping mechanism 26 and the base 27 may be made in a variety of ways, but I prefer to permit angular shifting of the match packets with respect to the base, and therefore pivot the packet-gripping mechanism upon the base. The pivotal action is provided by ears 41 bent down from the bottom plate 35, and carrying, pressed out from the ears, pivot balls 42 which seat in recesses 43 in the head 38 of the rubber base. The top of the head 38 has a plurality of rubber abutments 44, 45 and 46, any one of which may engage a stop 47 between the ears 41. Thus in Figure 2 rubber abutment 45 engages the stop 47 and the match packets extend directly outwardly from the surface to which the suction-gripping means is applied, while in Figure 4 the rubber abutment 44 engages the stop 47, and the match packets are angularly disposed with respect to the surface to which the suction-gripping means is applied. Shifting from the position of Figure 2 to that of Figure 4 is easy, since the rubber abutments are resilient and yield to permit the stop to pass from one abutment to the other. Once the stop is set against a given abutment, however, the resilient pressure of the rubber prevents shifting of the stop to another abutment unless considerable force is exerted.

To apply a match packet to the holder, I simply insert the free end of one of the tongues into the space between two separated folds of the match packet, and move the match packet with respect to the tongue in a direction laterally of the individual matches and longitudinally of the row of matches until the end of the match packet touches the intermediate portion 34 of the holder. Re-

versal of this process will remove an empty packet to permit substitution of a new packet.

The application of a match holder to a surface to which it is to be attached is accomplished 5 simply by pressing the holder toward the surface so as to flatten out the suction gripping flanges 39 and expel air from the cupped space 40. Subsequent resilient curving of the suction-gripping flanges 39 due to the tendency of the rubber

10 to restore the cupped shape of the flanges reduces the air pressure in the cupped space 40; and external air pressure holds the suction-gripping flanges against the surface to which they have been applied.

15 I find that the leakage of air is sufficiently slow so that a properly made suction-gripping device will hold upon a smooth surface (such as a glass window or desk top) for a period of weeks.

In order to prevent or decrease air leakage 20 into the cupped space 40, the gum at 39' should preferably be moistened, just before the suction-gripper is applied, to soften the gum. The gum (or other adhesive) assists in sealing the flat lower surface of the suction-gripper to the surface upon which it is applied. The gum also fills small irregularities in the surface, such as pores in wood, and prevents leakage due to such irregularities. In addition the gum serves an adhesive function.

25 When the gummed suction-gripper is properly applied, the bracket will stand much abuse, and retain its position for long periods on glass, metal, wood, etc.

30 During withdrawal of the matches by longitudinally pulling on the stick ends 20, a peculiar effect is observed which greatly enhances the value of the suction-gripping means. While the match is being withdrawn, the first important action of the suction-gripping means is to resist 35 the pull upon the match and prevent change in position of the match holder. As the match holder is light, it would be impossible to withdraw a match with one hand in many instances were it not for the tendency of the suction-gripping means to hold the match holder in the position in which it has been set. This feature of my 40 invention is particularly applicable to use in automobiles and in offices, where people frequently desire to strike a match while one hand is occupied upon some other purpose, such as driving a car, holding a telephone receiver, etc.

45 Besides the mere holding function which I have just described, the suction-gripping means assists in actual match striking. The match packets of the pull-and-light type are constructed so as to prevent withdrawal of the match until a considerable force has been exerted, so as to prevent the possibility that a match will be moving too slowly, when it passes over the match-striking 50 material, to ignite the match head.

55 During the initial part of the pull when a match is withdrawn, therefore, the suction-gripping means resiliently yields, increasing the size of the cupped space 40 and allowing the match holder 55 to move for a short distance toward the direction of pull. When the match begins to withdraw, the pull upon the match holder decreases, and the suction-gripping means draws the match packet rapidly away from the direction of pull.

60 Thus it will be evident that, at the time that the match head is moving over the match-striking material, the match is moving away from the packet due to the pull of the user and the packet 65 is moving away from the match due to the resilient return of the suction-gripping means to

its initial position. There is thus a highly desirable increased relative speed of movement between the match head and the match-striking surface, which gives a surer match-striking action than has been possible when the match packet 5 has been rigidly held.

It will be evident that the resilient action of the suction-gripping means may be applied to other types of match packet holders within my invention, and that my improved match packet 10 holder may be used with some other form of base than the rubber base shown. It will also be evident that the pivotal connection between the packet-gripping mechanism and the base is optional, although it is convenient, since it makes 15 the packet more adaptable.

Considerable variety is possible in the type of match packet to be used. In Figure 6 I show match packets united by metal bales 48, and having the match head exposed at the sides at 49, 20 whereas in the other packets shown, the sides are entirely enclosed. In each case, one fold or flap is separable from the remainder of the packet for insertion of the tongue 29.

In view of my invention and disclosure variations and modifications to meet individual whim or particular need will doubtless become evident to others skilled in the art, to obtain all or part of the benefits of my invention without copying the structure shown, and I, therefore, claim all 25 such in so far as they fall within the reasonable spirit and scope of my invention.

Having thus described my invention, what I claim as new and desire to secure by Letters Patent is:—

1. In a match holder, a base, a pair of laterally spaced generally parallel tongues secured to the base at opposite sides thereof and each adapted to enter between the folds of a packet of matches which light on withdrawal, a plate integral with 40 and at substantially right angles to the base, said plate extending below the tongues, generally parallel to the lower edge of the tongues and spaced from the tongues to hold the bottoms of match packets and extensions, one from either 45 side of the plate, parallel to the tongues and spaced from the tongues to follow the edges of the packets.

2. In a match holder, a rubber base having annular resilient cupped suction-gripping flanges, 50 a plate secured to the base, and a tongue secured to one end of the plate, spaced from the plate and extending in a direction longitudinally of the plate, whereby the plate supports the bottom of a packet of matches which light on withdrawal 55 and the tongue enters between the folds of the packet.

3. In a match holder, a rubber base having annular resilient cupped suction-gripping flanges and a plurality of rubber abutments, a tongue 60 adapted to enter between the folds of a packet of matches which light on withdrawal, means pivotally connecting the tongue and the rubber base and a stop engaging the successive rubber abutments and holding the tongue in a selected 65 pivotal position by the resilience of one of the rubber abutments.

4. In a match holder, a rubber base having annualr resilient suction-gripping flanges and a plurality of rubber abutments, a plate having 70 transversely extending ears pivotally connected to the base and having a stop between the ears engaging successive rubber abutments, and a pair of tongues parallel to and spaced from one another, secured at one end to the plate and ex- 75

tending with their edges, nearest to the plate, parallel to and in spaced relation to the plate, each adapted to receive and support a packet of matches which ignite on withdrawal.

5. A match packet having matches retarded against withdrawal and when the retardation is overcome withdrawable longitudinally past ignition material, to light the matches, a holder for the packet holding the matches in position for withdrawal longitudinally and a base for the holder uniting it resiliently in the direction of pull of the matches to a support, whereby, as a match is pulled the base is stretched away from its support until the retardation of a match in the packet begins to be overcome and then the packet recedes toward the support at the same time the match is withdrawn from the packet.

6. A match packet having matches retarded against withdrawal and when the retardation is overcome withdrawable longitudinally past ignition material, to light the matches, a holder for the packet having a laterally extending tongue adapted to fit transversely within the folds of the packet, holding the matches in position for withdrawal longitudinally and a base for the holder uniting it resiliently in the direction of pull of the matches to a support whereby as a match is pulled the base is stretched resiliently away from its support until the retardation of the match in the packet is overcome and then the packet recedes toward the support at the same time the match is withdrawn from the packet.

7. A holder for a match packet of the retarded pull and light type adapted to present the matches of the packet longitudinally perpendicularly with respect to a support and a base for the holder securing it to the support and resilient longitudinally of the matches whereby with pull upon the matches against their retardation the base is stretched resiliently and when the match begins to travel the base reacts to increase the relative speed of match travel across the ignition material.

8. In a match packet of the strike on withdrawal variety, folds making a cover for the packet, ignition material within the packet, in combination with a holder for supporting the packet having a tongue entering transversely to the length of the matches between the folds of the packet, a base secured to the holder, for supporting the packet in a position of withdrawal

movement longitudinally of the matches, the base being resilient away from its support and causing first a retarding action as the base is stretched and later a snap action of a match head with respect to the ignition material as the match leaves the packet and the resilient base is contracted.

9. A match packet comprising a row of matches adapted to be lighted upon withdrawal from the packet, and a wrap around the packet in combination with a match packet holder comprising a base, a tongue projecting into one side of the packet secured to the base extending from one side of the base across the base and separated from the base to provide a space for a layer of the packet between the tongue and the base when the tongue is within the outer fold of the packet and resilient pneumatic means spaced from the tongue and adapted to support the bottom of the packet from movement laterally of the tongue, holding the packet and providing resiliency between the support and packet when a match is pulled from the packet.

10. A match packet comprising a row of matches adapted to be lighted upon withdrawal from the packet, and a wrap around the packet in combination with a match packet holder comprising a base, a tongue of relatively thin metal, substantially wider than its thickness, said tongue penetrating the wrap of the packet in a direction transverse to the matches and supporting the packet against movement toward the stick ends of the matches and laterally of the matches, and resilient suction means for supporting the base of the tongue providing resiliency when a match is withdrawn from the packet.

11. A match packet comprising a row of matches adapted to be lighted upon withdrawal from the packet and a wrap around the packet in combination with a match packet holder comprising a tongue of relatively thin metal, substantially wider than its thickness, penetrating the wrap of the pull-and-light match packet in a direction transverse to the matches and supporting the packet against movement toward the stick ends of the matches and laterally of the matches and suction-gripping means for supporting the packet against movement toward the heads of the matches, upon withdrawal of the matches.

RODNEY S. PULLEN.
